UNITED STATES PATENT OFFICE.

WILFORD J. WINNINGHOFF, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

THERMOSTATIC ELECTRIC SWITCH.

Application filed November 10, 1923. Serial No. 673,900.

My present invention relates to switching apparatus for electrically heated appliances and especially for use with electrical flat irons, and provides means for disconnecting 5 the appliance on the attainment therein of temperatures which have become dangerously or excessively high.

A large percentage of fire loss today is caused by electric flat irons which left un- 10 attended reach excessive temperatures resulting in the ignition of tables or stands on which they are left or pieces of furniture or the floor on which they may have fallen and the ultimate destruction of property amount- 15 ing to enormous values. Numerous safety appliances are on market as part of electrical iron mechanisms or as auxiliary apparatus thereto whose intended purpose is to prevent fires which might be caused through 20 excessive temperatures reached in the irons which, however, have proven ineffective.

It is a purpose of my invention to provide means for opening a circuit which supplies electrically heated flat irons and the like au- 25 tomatically on the attainment therein of abnormal or excessive temperatures.

It is another object of my invention to pro- 30 vide means for cutting off such current au- tomatically at such high temperatures and leaving it off until turned on again by an attendant. I have shown my invention in the accompanying drawing which forms part of this application, and which shows in:

Fig. 1, a diagrammatic representation of 35 the application of my invention to a heater circuit;

Fig. 2, the application of my invention to electrically heated flat irons is diagrammati- 40 cally shown;

Fig. 3, a diagrammatic representation of a system similar to that of Fig. 1 but with a resistance in series with the mercury short-circuiting switch;

Fig. 4, a similar diagram in which part 45 of the heater resistance is used as the resistance of Fig. 3 in series with the shortcircuiting switch.

The electrical resistance heater 2 is connected to the supply mains 6 and 7 through 50 leads 8 and 9. Across these leads and in shunt to said resistance heater is the thermostatic switch 1, connected to leads 8 and 9 by leads 10 and 11, respectively. The said thermostatic switch 1 is a sealed vertical tubular

envelope of glass having the terminal elec- 55 trode 12 sealed through the wall thereof near its bottom and the terminal electrode 14 sealed through its wall near the top thereof. Within the said envelope is the body 13 of mercury contacting with said electrode 12 60 and normally at a level below the electrode 14. The quantity of mercury and the level thereof with respect to said electrode 14 at normal temperature or temperatures which are considered below the dangerous point is 65 predetermined so that the expansion of the mercury attending increases of temperature will bring the mercury to such a level that said mercury will contact with said electrode 14 and establish electrical connection there- 70 with when such temperatures become abnormal or dangerously excessive. In one of the leads from the supply mains between said main and the mercury switch 1 is connected the circuit breaker 3—4, and the suitable 75 switch 5 is provided in the circuit.

In Figure 2 is shown flat iron 15 having within body 16 thereof the electric heating element 2 connected by leads 8 and 9 to the connection pins 17. In lead 9 is the circuit 80 breaker 3—4, and between said circuit breaker and heating element is connected the thermostatic mercury switch 1, across said leads 8 and 9 and in shunt with said heater 2. Connected to said connection pins 17 is 85 shown diagrammatically the source of current 18. The handle 19 serves to close contactor 4 of the circuit breaker 3—4.

In the operation of my invention the electric iron is connected by means of pins 17, 90 or other suitable equivalents, and a corre- 95 sponding part to the source of electric current and the iron used in the usual way. The iron being cold the level of mercury in switch 1 is below electrode 14 and the circuit through said switch is open. The contactor 4 of cir- 100 cuit breaker 3—4 is, of course, closed. Should the iron reach a temperature during the use thereof which is above a predetermined point the mercury 13 will expand sufficiently to close the circuit through switch 1 thereby short-circuiting the electric heater 2 and shunting circuit breaker 3—4 across the supply mains 6 and 7. Abnormal current then passing through solenoid 3 of said circuit 105 breaker the contactor 4 thereof will be opened and left open until manually closed by the operator through handle 19 as diagrammati-

cally shown in Figure 2. Should the contactor 4 be again closed before normal temperature is approached in the iron and mercury 13 has receded through contact 14, sole-
5 noid 3 will continue to function to open contactor 4 until such temperature has been ap-
10 proached and the level of mercury 13 has receded from electrode 14 to open the circuit through switch 1. Likewise should the iron
10 be left or forgotten with the source of current connected to the heater the switch 1 and sole-
noid 3 will function to operate to open contactor 4 upon the reaching of abnormal or
dangerous temperature in the manner de-
15 scribed above.

As shown in Fig. 3 I employ in circuits where there is possibility of a fuse blowing out before the circuit breaker 3-4 operates to open the circuit, a resistance 15 in series
20 with the switch 1 between leads 8 and 9. This resistance is used to limit the current passing through the circuit shorted on the closing of
switch 1 to the current necessary for the operation of the circuit breaker. And as shown
25 in Fig. 4 where conditions require or allow I use a part of the heater resistance as the resistance for limiting the current through
switch 1, the lead 10 being connected to a point intermediate the ends of the heater
30 resistance 2.

While I have shown the circuit breaker as opening one side of the circuit main I use when required a breaker for opening both sides of the main circuit and operated by a
35 coil or coils in either or both of the lines. Such an arrangement is made by providing the armature of circuit breaker 3-4 with mechanical connection with a switch in main
8 of Figure 1 for the opening thereof by said
40 armature simultaneously with the opening of switch 4.

I claim:

1. In an electric heater circuit, in combina-

tion, an electric resistance heater, a tempera-
ture closed switch in shunt with said heater, 45
and a circuit breaker in a lead to such heater
and switch actuated by the flow of abnormal
current therethrough.

2. In an electric heater circuit, in combina-
tion, an electric heating means, a thermostatic 50
mercury switch in shunt with said heater,
said switch being open at normal tempera-
tures and closed at predetermined higher tem-
peratures, leads to said heater and switch, and
a current actuated circuit breaker in one of
55 said leads actuated by the flow of abnormal
current therethrough.

3. In an electric flat iron, in combination,
an electric heater in the body of said iron, a
thermostatic switch in close proximity to said
heater and electrically shunted across said
heater, leads through said heater and switch
60 and terminals therefor, and means in one of
said leads for opening a circuit therethrough
upon the shunting of said heater and said
thermostatic switch.

4. In an electric flat iron, in combination,
an electric heater for said flat iron, a thermo-
static mercury switch positioned near said
heater and electrically shunted there across,
70 leads to said switch and heater, and a current
controlled circuit breaker in one of said leads
actuated by abnormal increases of current
flow therethrough.

5. In an electric heater circuit, in combina-
tion, an electric resistance heater, a tempera-
ture closed switch in shunt with said heater
and a circuit breaker in a lead to said heater
and switch said circuit breaker comprising a
80 solenoid and a contactor which are in series
with each other in the lead in which they are
connected.

Signed at Hoboken, in the county of Hudson
and State of New Jersey, this 9th day of
November, A. D. 1923.

WILFORD J. WINNINGHOFF.
